UNITED STATES PATENT OFFICE

168,412

WINDOW SASH FREEING TOOL

Oscar J. Le Boeuf, Gary, Ind.

Application November 21, 1950, Serial No. 13,080

Term of patent 14 years

(Cl. D22—1)

To all whom it may concern:

Be it known that I, Oscar J. Le Boeuf, a citizen of the United States, residing at Gary, in the county of Lake and State of Indiana, have invented a new, original, and ornamental Design for a Window Sash Freeing Tool, of which the following is a specification, reference being had to the accompanying drawing, forming part thereof.

Figure 1 is a top plan view of a window sash freeing tool showing my new design;

Figure 2 is a side elevational view thereof; and
Figure 3 is a bottom plan view of the same.

The characteristic features of the design reside in the head portion of the window sash freeing tool having the configuration shown.

I claim:

The ornamental design for a window sash freeing tool, as shown and described.

OSCAR J. LE BOEUF.
